MOP

Ralph F. Henn, Geneva, Ohio

Application March 8, 1935, Serial No. 10,084

5 Claims. (Cl. 15—147)

This invention relates to mops, particularly dust mops, and among other objects aims to provide an improved mop having a swab which may be easily removed and having a swab carrier or frame which is flexibly mounted on the handle so as to permit movement thereof in many directions, thus permitting the mop to bend or twist relative to the handle to conform to the varying angles of surfaces being cleaned by the mop. The invention has other objects which will be pointed out in the following description of a preferred embodiment thereof.

In the accompany drawing.—

Fig. 1 is a plan view of the mop, the yarn there-
of being indicated more or less diagrammatically, the larger portion of the handle being omitted;

Fig. 2 is a plan view on an enlarged scale showing the swab frame and the handle connector or socket member and omitting the swab;

Fig. 3 is a view similar to Fig. 2 but showing one end of the swab frame disconnected from the handle connector to facilitate placing or removal of a swab;

Fig. 4 is a fragmentary view showing the construction of the swab; and

Fig. 5 is an enlarged detail showing the hook for detachably holding the end of the swab frame.

Referring particularly to the drawing, there is shown a mop comprising a handle 10, handle connector or socket member 11, a swab frame 12 and a swab 13. The swab comprises a coiled wire forming a core 14 on which cotton yarn 15 is secured prior to the coiling operation by the process disclosed in the patent to Carter No. 1,209,639, the result being that the yarn completely covers the coiled wire and extends outwardly from the wire core in all directions, as disclosed in my Patent No. 1,936,509 dated November 21, 1933.

The handle connector or socket member 11 is preferably formed of heavy nickel-plated wire coiled in a double spiral coil, with a tapered neck 16 at one end. The diameter of the spiral coils is such that the end of the handle 10 is easily received within the coils, particularly if the handle is introduced with a slight twisting motion. A reverse twist of the handle will, however, cause the coils to tighten and grip the handle very securely so that removal is impossible. The tapered neck 16 serves as a stop to the handle and provides a resilient connecting means between the socket member 11 and the swab frame 12, as will be described.

In the preferred embodiment of the invention the wire forming the resilient tapered neck 16 is continued to form the swab frame 12 which is nothing more than a wire loop. Obviously, manufacturing economies are realized by making the wire frame integral with the connector; however, it is within the scope of the present invention to make the wire frame a separate piece and unite it to the connector. In the preferred embodiment, a single piece of wire is bent intermediate its ends and then two of its lengths are twisted spirally to form the handle socket and one end of said wire terminates at the end of the tapered neck 16, said end being formed into a hook 17 which lies in the plane of the loop. The end of the wire extension which forms the swab frame 12 is provided with an eye 18 which is adapted to engage the hook 17 to close the loop. Instead of a hook and eye connection, two hooks or any other simple means may be used for connecting the ends of the frame together; a hook and eye connection is preferred because of its extreme simplicity and ease of manufacture. When desired the loop may be opened by merely disengaging the eye from the hook, whereupon the swab frame will have the form shown in Fig. 3, with the free end ready for insertion in the core of the swab. Obviously, the eye 18 should be of sufficiently small diameter to pass freely through the wire core 14 of the swab, which is inserted upon its frame by a pushing motion. If the wire is bent so that when the loop is opened, the wire naturally assumes a curvilinear form with a narrow gap between the free end of the loop and the socket, as shown, closing of the loop after the swab is in place will be greatly facilitated and opening of the loop will also be made easier, as the wire will not spring open with great force; and of course insertion and removal of the swab will also be easier if the wire loop is easy to control. However, it is within the scope of the invention to employ a wire frame with no natural tendency to form a loop.

As stated above, the swab is mounted on a spiral wire core which has a normal length greater than the perimeter of the swab frame 12, that is to say, the swab, when in repose, has a total over all length preferably several inches in excess of the length of the wire frame 12. The result is that when the swab is inserted on its frame, it must be compressed longitudinally to permit the eye 18 to engage with the hook 17 and hence the swab is permanently pressed at both ends against the end of the connector so that the yarn of the swab completely hides the con-

nection between the swab frame and the handle socket member. The yarn may also be long enough to normally close the space in the interior of the swab frame, although this is not necessary.

When the user of one of these mops desires to remove the swab, this is easily done by merely disengaging the eye 17 from its hook, whereupon the loop more or less straightens out and the detached swab is then easily pushed off of its frame. The swab may be put in a washing machine and washed and may even be wrung through a wringer, before replacing it upon the swab frame. The ends of the wire of the core 14 are turned inwardly so that they will not catch on anything or scratch furniture. A further and very important advantage of the mop is the extreme flexibility of the connection between the handle and the mop frame. This connection may be bent in all directions radially relative to the handle, the result being that the mop frame may swing in any direction with respect to the handle, thus permitting the swab to conform to surfaces at various inclinations relative to the handle axis. Furthermore, the connection is unbreakable, the resiliency of the wire being such that it will yield without ever breaking. Moreover, the wire loop itself is flexible, permitting a slight yielding thereof to blows. The swab frame is always protected by the yarn of the swab and can never be exposed unless the user forcibly pulls apart the two juxtaposed ends of the swab which are normally substantially in contact adjacent the hook and eye connection. The described mop is extremely inexpensive to manufacture and has many advantages over mops heretofore known.

Obviously, the present invention may be embodied in many forms neither shown nor described but within the scope of the appended claims.

Having described one embodiment of my invention, what I claim as new and desire to secure by Letters Patent is:—

1. A mop frame comprising, in combination, a handle-receiving socket made of a resilient wire wrapped in a spiral coil; a hook on said socket, and a swab holder formed from an integral extension of said socket, which extension is bent around in a substantially circular flexible loop

and has its free end detachably engaged with said hook.

2. A mop frame comprising, in combination, a handle-receiving socket; a flexible wire frame in the form of a loop, one end of which is permanently secured to the socket and the other end of which is adapted to be threaded into a swab and is detachably secured to the socket; the wire of said frame being so bent that when the detachable end is freed from the socket, the loop opens to provide a relatively narrow gap which is permanently maintained narrow by the resilience of the wire, said gap facilitating insertion and removal of a swab and connecting and disconnecting the detachable end.

3. A mop frame comprising, in combination, a handle-receiving socket; said socket having a flexible neck made of coiled wire; said wire extending beyond one end of the neck and bent around to form a loop; a hook projecting from the aforesaid end of said neck substantially in the plane of said loop; the free end of said wire being detachably connected to the hook.

4. A mop comprising, in combination, a resilient elongated member formed into a loop with its ends separably united to form a swab frame which is adapted to be mounted on one end of a handle; and a swab supported on the swab frame and having an internal expansile coil spring of such length that it is compressed when on the frame, thereby normally completely covering the frame.

5. A mop frame comprising, in combination, a handle-receiving socket made from a piece of resilient wire doubled and bent to form a double spiral coil; one end of said wire terminating near the end of the socket opposite to the end which receives the handle and having a hook formed at its extremity; the other end portion of the wire projecting a sufficient distance beyond the hook to provide a swab-holding loop; the extremity of said other end portion having a hook thereon to engage the first named hook; the resilience of said wire resisting engagement of the hooks so that when said hooks are disengaged the loop will open and remain open until deliberately closed.
